MILL TABLE POSITION INDICATING DEVICE

Francis L. Moseley, 700 Flintridge Ave., Pasadena, Calif. 91103, and Peter Moseley, 1369 Skywood Circle, and Glenn A. Johnson, 2163 N. Altadena Drive 91001, both of Altadena, Calif.

Filed Oct. 31, 1967, Ser. No. 9,226

Term of patent 14 years

(Cl. D55—1)

FIG. - 1

FIG. - 2

FIG. - 3

FIG. - 4

FIG. - 5

FIG. - 6

FIG. 1 is a perspective view of a mill table position indicating device showing our new design;

FIG. 2 is a top plan view thereof;

FIG. 3 is a front elevation view thereof;

FIG. 4 is a view of the left side thereof;

FIG. 5 is a rear elevation view thereof; and

FIG. 6 is a view of the right side thereof.

The dominant features of our design reside in the portion shown in full lines only.

We claim:

The ornamental design for a mill table position indicating device, substantially as shown and described.
